MOUNT FOR ELECTRON DISCHARGE DEVICES

Barbara W. Wall, Owensboro, Ky., assignor to General Electric Company, a corporation of New York

Application October 14, 1955, Serial No. 540,512

5 Claims. (Cl. 313—261)

My invention relates to electron discharge devices and more particularly to mounting structures for said electron discharge devices.

One of the problems encountered in manufacturing electron tubes is that of maintaining the electrode elements in proper spaced relation. This problem becomes more pronounced in grid-alignment type receiving tubes where lateral wires of two or more grids must remain in relatively the same position during operation when the tubes may be subjected to considerable vibration, shock impact, and substantial stress due to acceleration and deceleration of units in which the tubes are mounted. Such forces may result in changing the relative position of the electrode elements with respect to each other. Any change in the relative positions of the electrodes results in a change of the tube characteristics, which, of course, is undesirable. Therefore, it is of prime importance that the tube be constructed such that the electrode elements are held in a set predetermined position.

It is, accordingly, a principal object of this invention to provide a means and methods for imparting rigidity and mechanical strength to the electrode assembly of electron tubes.

Another object of this invention is to expedite assembly of the electrode elements of electron tubes.

Still another object of this invention is to provide an efficient, inexpensive, means and methods for assembling the electrode elements within a tube envelope.

Yet another object of this invention is to provide a means for maintaining the electronic characteristics unchanged during the life of an electron tube.

Further objects and advantages of my invention will become apparent from the following description and the features of novelty which characterize my invention will be pointed out with particularity in the claims annexed to and forming part of this specification.

In carrying out the objects of my invention I provide a novel support member for securely positioning the grids in the mica spacers.

For a detailed explanation of my invention, reference is made to the accompanying drawings in which:

Figure 1 is an elevational view, partly in cross-section, of an electron discharge device embodying features of my invention;

Figure 2 is a cross-sectional view taken along the lines 2—2 of Figure 1;

Figure 3 is an enlarged isometric view of one embodiment of the invention;

Figures 4a, 4b, 4c are enlarged elevation views showing steps in the process of assembly of the embodiment of Figure 3;

Figure 5 is an enlarged isometric view of another embodiment of my invention;

Figure 6 is an enlarged elevation view of the embodiment of Figure 5 in final assembly;

Figure 7 is an isometric view of yet another embodiment of my invention; and

Figure 8 is an enlarged elevation view of the embodiment of Figure 7 in final assembly.

Figure 1 shows an electron discharge device envelope 11 within which is positioned a mount assembly 12 including an anode 13, a cathode 14, and wire wound coaxial grids 15, and 16 supported by vertical rods 17 and 18, respectively, which extend through transversely disposed mica spacer plates or supports 21 and 22.

The anode 13 may be in the form of a cylinder, and 10 engages mica spacer plates 21 and 22 at opposite ends of the cylinder. As seen in Figure 2, the mica support has spaced apertures through which the various electrode supports extend for the purpose of maintaining electrodes in spaced relation with respect to each other. Spacer plates 21 and 22 press firmly on the glass envelope to maintain the electrodes in separated spaced relation to the glass envelope. The connecting wires to the various electrodes may be of conventional design and are not, per se, a part of this invention.

20 In accordance with one embodiment of my invention J-shaped support members 23 are affixed to the portions of the grid support rods 17 and 18, which extend through the apertures in mica plates 21 and 22. The enlarged view of Figure 3 clearly shows the J-shaped support member 23 of my invention. Figures 4a, 4b, and 4c are enlarged elevation views of the J-shaped support member 23 and the portion of rod 17 extending upwardly through the aperture in mica support 21, and shows the process of assembly. The J-shaped member 23 is initially placed adjacent to the rod 17 so as to bear against the spacer plate 21 and leg 25 of the member 23 is spot-welded, as shown in Figure 4a. The free end 24 of member 23 is next bent against the leg 25 of member 23 to form a bight 26 (Figure 4b), and spot-welded to the rod 17 at a point below the first-mentioned weld. Bight 26 is next forcefully deformed to wedge against the leg portion 25 of the member 23, Figure 4c, and spotwelded at a point on the rod 17 near the spacer 21, thus rigidly fixing rod 17 to the mica plate 21. A similar member 23 is 30 similarly affixed to the opposite end of rod 17 and wedged against mica plate 22.

While the invention is described in detail as used in affixing grid electrodes, it will be understood that the invention is applicable for use in fixing any other type 40 electrodes such as cathodes or anodes having portions which extend through a transverse supporting plate.

The vertical rods 17 are thus rigidly fixed to mica supports 21 and 22 and inhibit any vertical movement of the grid as well as serving as a means of grid alignment. 50 Because the rods 17 are held rigidly there will be no internal sag in the rods and the grid wires 15 will maintain a predetermined spaced relation with respect to each other and to the other electrodes. Once assembly of the various support members 23 is completed, it is assured 55 that a proper mounted relation exists between the various electrodes and also assures a rugged electrode assembly.

It will be seen that the pressing in of the bight portion 60 26 against the rod 17 and the welding thereof to the rods results in a deformation of the mica 21, as shown at 19.

Each deformation of the mica effects a tight clamping action on the rod 17.

The U-shaped member 27 of Figure 5 is another embodiment of my invention. The process of assembly is similar to that previously described for the J-shaped member, Figure 3, excepting that the bight 28 is formed prior to welding the member to the electrode rod 17. The final assembly is shown in Figure 6. This embodiment, it will be noted, requires but two spot welds per member instead of the three welds needed in the above-described embodiment.

70 The arcuate shaped member 31 of Figure 7 is still another embodiment of my invention. To assemble member

31, the upper end portion of said member is welded to the rod 17, and the lower end bears on the surface of the plate 21. After welding, the member is straightened out to wedge against the plate 21, Figure 8, to produce the deformation of the mica 21, ensuring tight clamping.

Although the present invention has been illustrated by specific examples, it will be obvious to those skilled in the art that modifications may be made without departing from the spirit thereof.

What I claim as new and desire to secure by Letters Patent of the United States is:

1. An electron tube mount assembly comprising a planar insulator including an aperture, an electrode including a support portion extending through and tightly fitted in said aperture in said insulator, a clip member having an end portion affixed to one end of said support portion of said electrode, said clip member extending contiguously along the length of said support portion to a point substantially below the normal plane of the corresponding side of said insulator, whereby said clip member is effective for substantially depressing the edge of said insulator at said aperture out of said normal plane and into wedging engagement with said support portion of said electrode for increasing the tightness of said fit.

2. An electron tube mount assembly comprising a planar insulator including an aperture, an electrode including a support portion extending through and tightly fitted in said aperture in said insulator, a clip member having an end portion affixed to one end of said support portion of said electrode, said clip member including an opposite end portion of a folded double thickness secured to said support portion of said electrode and extending contiguously along the length thereof to a point substantially below the normal plane of the corresponding side of said insulator, whereby said opposite end portion of said clip member is effective for substantially depressing the edge of said insulator at said aperture out of said normal plane and into wedging engagement with said support portion of said electrode for increasing the tightness of said fit.

3. The method of mounting an electrode in an insulative spacer comprising the steps of tightly fitting one end of said electrode in an aperture in said spacer, securing to said end of said electrode a separately formed elongated clip member having an arcuate free end with said free end in abutting engagement with the corresponding surface of said spacer, forcibly deforming said arcuate free end of said clip member into straight contiguous engagement with said electrode and securing said free end to said electrode whereby said free end is extended lon-

gitudinally along said electrode to a point whereat said free end is effective for substantially depressing the corresponding edge of said spacer at said aperture out of the normal plane thereof and into wedging engagement with said electrode.

4. The method of mounting an electrode in an insulative spacer comprising the steps of tightly fitting one end of said electrode in an aperture in said spacer, securing to the end of said electrode a substantially J-shaped member having a straight portion and bight portion with a free end, with the bight portion abutting the corresponding surface of said spacer, bending the free end of said bight portion into engagement with said straight portion and securing said free end to said straight portion and electrode, and forcibly deforming said bight portion into straight contiguous engagement with said straight portion and securing same to said straight portion and electrode for effectively elongating said member along said electrode, thereby to depress the corresponding edge of said spacer at said aperture out of the normal plane thereof and into wedging engagement with said electrode for increasing the tightness of the fit of said electrode in said spacer.

5. The method of mounting an electrode in an insulative spacer comprising the steps of tightly fitting one end of said electrode in an aperture in said spacer, forming a clip member as a U-shaped element, compressing the straight portions of said element together and securing same to an end of said electrode with the bight portion of said element in abutting engagement with the corresponding surface of said spacer, forcibly deforming said bight portion into straight contiguous engagement between said straight portions and with said electrode and securing said straight and bight portions to said electrode for substantially depressing the corresponding edge of said spacer at said aperture out of the normal plane and into wedging engagement with said electrode for increasing the tightness of the fit of said electrode in said spacer.
